(57) **CLAIM**

We claim the ornamental design for a handle for a portable dialysis cabinet, as shown and described.

DESCRIPTION

FIG. 1 is a perspective view of a handle for a portable dialysis cabinet according to one embodiment;

FIG. 2 is a perspective view of a handle for a portable dialysis cabinet shown in a collapsed position;

FIG. 3 is a rear view of the handle of the portable dialysis cabinet referenced in FIG. 2;

FIG. 4 is a left side view of the handle of the portable dialysis cabinet referenced in FIG. 2;

FIG. 5 is a right side view of the handle of the portable dialysis cabinet referenced in FIG. 2;

FIG. 6 is a top view of the handle of the portable dialysis cabinet referenced in FIG. 2;

FIG. 7 is a perspective view of a handle of a portable dialysis cabinet shown in an extended position, as referenced in FIG. 1;

FIG. 8 is a front view of the handle of the portable dialysis cabinet referenced in FIG. 7;

FIG. 9 is a rear view of the handle of the portable dialysis cabinet referenced in FIG. 7;

FIG. 10 is a left side view of the handle of the portable dialysis cabinet referenced in FIG. 7;

FIG. 11 is a right side view of the handle of the portable dialysis cabinet referenced in FIG. 7; and,

FIG. 12 is a top view of the handle of the portable dialysis cabinet referenced in FIG. 7.

In the drawings, the broken lines depict unclaimed subject matter only and form no part of the claimed design.
